ELECTRIC CIRCUIT FOR POLARIZED COMPOUND ELECTROMAGNET

Filed Jan. 7, 1944

FIG. 1.

UNITED STATES PATENT OFFICE

2,419,258

ELECTRIC CIRCUIT FOR POLARIZED
COMPOUND ELECTROMAGNET

Oscar S. Field, Rochester, N. Y., assignor to General Railway Signal Company, Rochester, N. Y.

Application January 7, 1944, Serial No. 517,388

7 Claims. (Cl. 175—335)

1

This invention relates in general to improved light signals adapted for use on railways, and has more particular reference to improvements in search light signals of the "SC" type.

The signal disclosed in the present application is to be considered in the nature of an improvement over the signal of the same general type disclosed in my prior application Ser. No. 361,060, filed October 14, 1940, now Patent No. 2,376,534, dated May 22, 1945, and no claim is intended to be made in this application covering any subject matter common with such prior application.

One of the objects of the present invention is to provide means for interconnecting the spectacle and the two operating armatures of this type of light signal, so as to provide a simple, economical, rugged, and long-lived device.

Another object of the present invention is to provide means, largely of a structural nature, whereby temporary loss of shunt in a track circuit will not cause an improper and undesirable operation of light signals of this type when controlled by a track circuit.

Further objects, purposes and characteristic features of the present invention will appear as the description progresses, reference being made to the accompanying drawings showing, solely by way of example, and in no way whatsoever in a limiting sense, one form which the invention can assume. In the drawings:

Fig. 1 is a fragmentary, diagrammatic view of the embodiment of this invention.

Fig. 2 is a fragmentary view of a connection constituting part of this invention.

Fig. 3 is a sectional view, on lines 3—3 of Figs. 1 and 2, and viewed in the direction of the arrows.

Fig. 4 is a circuit diagram, showing one application of the improved light signal in accordance with this invention.

Figs. 5 and 6 are respectively fragmentary plan and front elevational views of a detail of construction.

Fig. 7 is a fragmentary sectional view on line 7—7 of Fig. 8, viewed in the direction of the arrows of a second detail of construction.

Fig. 8 is a fragmentary front elevational view of the second detail of construction.

Referring now to the drawings and first to Fig. 1, there is here shown a portion of a signal in accordance with this invention with only those parts shown that are necessary for a complete understanding of the invention. The signal includes a red-yellow electro-magnetic operating member RY and a similar yellow-green operating member YG.

2

The red-yellow operating member includes core portions 3 and 4, below which is pivoted, as by pivots 5, an armature 6 and shown in the drawing in its retracted position. In like manner, the yellow-green operating member includes core portions 7 and 8, and an armature 9 having pivots 10, and this armature likewise is shown in its retracted position. As in the above referred to application, the armatures are moved magnetically to their attracted positions when their operating coils (not shown in this figure) are energized, unless otherwise prevented from assuming such positions.

A usual light control spectacle 11, carrying colored transparent roundels R, Y and G, respectively colored red, yellow and green is connected at its lower end 12 to a shaft 13, carried on pivots 14. Upon rocking of shaft 13 the spectacle is swung to progressively bring the colored roundels 15 opposite a light source, as represented at 16, to thereby display either a red, yellow or green aspect.

The shaft 13 carries an off-set crank, having two arms 16 and 17. The crank arm 17 is pivoted to the depending stem portion 18 of a T-shaped floating lever, having its head formed by oppositely extended arms 19 and 20, the arm 19 being pivoted to armature 6 and the arm 20 being pivoted to armature 9. These arms are pivoted to 30 their armatures by universal or ball and socket joints one of which joints is shown in detail in Figs. 2 and 3.

The joint connecting arm 19 to armature 6, is constituted by a ball 21 which has a driven fit 35 into a cylindrical hole 22, which hole is symmetrically positioned with respect to a flat sided slot 23 extending inwardly a considerable distance beyond the inner end of the hole. Slot 23 receives the free end of arm 19, which free end is bifurcated to have upper and lower fingers 24 and 25 spaced from each other sufficiently to be received over the ball 21 with sufficient clearance to permit easy movement of the fingers on the ball. The inner faces of the fingers 24 and 25 are arcuate in form so as to conform to the contour of the bearing ball 21 with the slight clearance above stated. With the construction as just described, it is clear that the joint between arm 19 and armature 6, constitutes a universal joint and permits free pivoting of the two members with respect to each other, the ball received in the armature bore with a driven fit being fixed with respect to the armature.

In the same manner, arm 20 is pivoted at its 50 outer end to armature 9 by a ball and socket

joint including a ball 26 on which is received the forked or bifurcated end of arm 20. The arms 19 and 20 as well as the balls 21 and 23 are made of non-rusting material as brass or bronze while the armatures 6 and 9 are of magnetic and rustable material. Thus, the ball joints are so made as to avoid any sliding of parts that are of rustable material in order to minimize friction. It is contemplated, however, that the arm 19, for example, could be tight on the ball 21 and the ball be loose enough in the armature to both slide and rotate. Also, if desired both the ball and the end of the arm could be loose, respectively, in the armature and on the ball. In each case, it follows that on the movement of either armature, the arms are free to turn and to slide, which action is necessitated not only because of the armatures being constrained to movement in a vertical plane, but also due to the connection to the crank arm 16. Thus, each joint constitutes a sliding universal joint. It should be noted that the end of arm 19 (Figure 2) is sufficiently spaced from the inner end of slot 23 to prevent it striking the end of the slot. The same is true of arm 20.

With the above described construction it appears clear that, upon either of the armatures 6 or 9 assuming attracted position, depending arm 18 of the floating lever is raised to rock shaft 13 and shift the spectacle with respect to the light source 15 and upon the picking up of the other armature while the first armature is up, the spectacle is moved a further distance. The parts are so proportioned that the spectacle which is biased when the signal is deenergized to display the red indication, is moved sufficiently to display a yellow indication upon the energization of either operating member, and to shift it a further distance to display a green indication upon the contemporaneous energization of the other operating member.

As described above the spectacle is carried by one end of shaft 13 while the other end of the shaft is connected by means of the crank 16 to the operating armatures. This showing is wholly schematic and shows no detail of actual construction.

The connections just referred to in one actual form of construction will now be described in connection with corresponding figures of the drawings.

As shown in Figs. 5 and 6, the connection between the depending portion 18 of the floating lever and shaft 13 includes a pivot pin 60 held in spaced ears 61 and 62 which are formed on the crank proper. The crank is constituted essentially of a ribbon loop 64 of spring material formed in the shape of an open-ended loop, with the ears carried by one of its ends. The loop 64 has its other end held in a slot 65 in shaft 13 by suitable means as rivets 66 and an adjusting screw 67. The adjusting screw 67 passes through the lower arm of loop 64 and is threaded through shaft 13. On this screw is a lock nut 68 for holding the screw in adjusted position. The loop is biased to a wider open position than that shown in the drawing whereby by turning the screw inwardly or outwardly the loop is held more contracted or is allowed to expand to thereby turn shaft 13 and with it the spectacle 11. In this manner the initial or deenergized position of the spectacle can be accurately adjusted by means of screw 67 and the adjustment dependably maintained by means of lock nut 68.

Referring now to Figs. 7 and 8, there is here

shown one actual form of construction for connecting spectacle 11 to the operating shaft 13. At the end of the shaft is a flat faced plate 71, which is integral with or fixed to the shaft. 5 Against the face of plate 71 is a friction plate 72 of fibre or relatively soft metal such as copper or the like, while against the face of the friction plate 72 is a brake plate 73. The plates are fastened together near one edge by a screw 10 74 which snugly fits its receiving holes in the plates to thereby form a pivot connection. Sleeved on screw 74 between plate 73 and the screw head is a coil spring 75 which operates to press the plates together with a suitable degree of pressure.

Near an opposite edge of the plates is a screw 15 76 which is snugly received in receiving openings in plates 71 and 72 but loosely received in an opening in brake plate 73, as indicated at 20 77. It is clear from this that brake plate 73 can slide with respect to the plates 71 and 72 to a limited extent, as defined by screw 76 and its receiving opening in plate 73.

As seen most clearly in Fig. 8, shaft 79 of 25 the spectacle is carried by braking plate 73 by means of a receiving jaw 80 and a spaced receiving jaw 81 carrying clamping screws 82, thereby to securely fix the spectacle to the braking plate.

Upon the spectacle moving to either extreme 30 position, any tendency for the spectacle to rebound and thereby adversely affect the signal indication, is effectively prevented by the absorption of the energy of the moving parts by 35 friction as the braking plate slides on plate 72. This frictional movement of the plates takes place in one direction when the spectacle moves to its deenergized position and in the other direction when the spectacle moves to its fully energized or clear position. Thus, the connection of the spectacle to the shaft is by means of frictional break-down connection restrained to a limited amount of relative motion, and all re-bound and vibration is effectively prevented.

40 It follows, therefore, that the energization of but one operating member changes the signal aspect from red to yellow, and the contemporaneous energization of both operating members produces a green signal indication.

45 In order that the signal shall not swing from red to green momentarily and then return to yellow, under certain transient conditions and thus produces a flash of the green, means is provided to prevent this confusing and undesirable operation. This means is constituted by a structural interlock or loading arm, whereby armature 9 cannot pick up until after armature 6 is already picked up. This loading structure comprises a rigid arm 28 in the form of a channel fastened 50 to the under part of the front end of armature 9 by a screw and nut 29, constituting in addition to a fastening means an adjustable front stop for the armature and by rivets or pins 30 and 31 constituting usual residual pins, in addition to being fastening means. The rigid arm 28 extends across the gap between the two armatures and bears against the lower face of armature 6 when this armature is in released position. The free end of arm 28 is cut out as shown in Fig. 1 and is of the proper length to prevent any side play of the armatures causing interference with the arm by the front stop 33 and pins 32, 32. In this manner, armature 9 is loaded with the weight of the armature 6, in addition to the 55 spectacle and its own weight, and hence through 60 70 75

its operating coil be energized, it will not pick up until after armature 6 has picked up.

Armature 6 carries usual residual pins as 32 and an adjustable front stop 33 of the same type as described above in connection with armature 9.

The significance and advantages of this improved form of spectacle operating means, in this search light type of signal can be most readily understood from considering an example of its application in practice.

In Fig. 4 is shown one application of this improved form of signal structure. There is here shown a stretch of single track constituted by track rails 34 separated into usual isolated track sections by insulating joints 35, one complete section B and the adjacent ends of sections A and C, being shown. Section B includes a source of energy 36, an adjustable resistance 37 and a track relay 38, in the usual manner. Sections A and C are, of course, likewise constituted although the drawing fails to so show them. In connection with the entrance end of section B, is a wayside signal of the type and construction as described above. This signal is controlled in the usual manner by traffic conditions in its own block B and the two blocks next in advance and so arranged as to display a red indication when its block is occupied, as in the condition shown in the drawing, as note the vehicle 39. It displays a yellow indication when its block is unoccupied but the block next in advance is occupied, and to display a green indication when its block and the block next in advance are both unoccupied.

The signal shown in Fig. 4 is of the polarized type, the yellow-green operating member YG having an energizing winding 41 so poled with respect to a permanent magnet 42 as to operatively respond only to energy of one polarity which can be characterized as normal or positive polarity. The operating member RY has an energizing winding 43 which is connected to the output side of a rectifier 44 of the full-wave type, connected to both windings as shown in the figure of drawing and as disclosed in detail in the application above referred to.

Accordingly, as so disclosed in this referred to application, energy applied to the signal through wire 45 and of negative or reverse polarity causes operation only of the RY operating member, while energy so applied of normal or positive polarity causes operation of both operating members to respectively change the signal aspect from red to yellow, and from yellow to green.

In the operation of the signal in the situation shown, it may occur in practice that a short train or single vehicle, particularly if light and travelling at high speed on passing out of block B and into block C, may cause the track relay 38 of the vacated block to pick up before the track relay of the newly occupied block C has released. In this case, there is a temporary loss of shunt, and the condition temporarily is the same as if the vehicle had been lifted clear of the track. This condition exists until after the track relay for block C has released, and the signal for block C has responded to this release and its operating member RY has released to thus pole change the current applied to wire 45 through wire 451 from the temporary or transient condition of normal or positive polarity to the proper negative or reverse polarity.

Under the above mentioned transient condition, the two operating members of the signal for block B are energized and both armatures

would, if not prevented, pick up and the signal would display a green indication. So soon as the temporary condition ceased to exist, the signal would then swing back to its yellow position.

5 Thus the signal for block B would cause an undesired and unintended flash of the green. The electro-magnet for the RY operating member is made slower to respond to energy than is the YG operating member, and further is slower to pick up than it is to release. This is accomplished in any desired or well-known manner, as by means of a short circuited low resistance winding or slug 47 on the core 48 of the member, in connection with proper adjustment of the applied energy 15 level, air gaps, etc. all as are recognized by those versed in this particular art. Accordingly, while the windings of the two operating members are both energized for a short period of time under the transient condition referred to the RY operating member is slow enough to pick up to bridge over this temporary period and due to the effect of the loading arm 28, the armature of the yellow-green operating member cannot pick up, the RY member armature preventing it from so doing. Thus, the signal for block B, under the stated 20 conditions, responds properly to traffic conditions and moves only from red to yellow positions, and any undesired and unintended flash of the green is wholly prevented.

25 In Fig. 4 has been shown but one example of the application of this improved structure, there being other applications where it is very desirable, as for instance, in connection with intermittent inductive train control systems. This application is set forth in detail in an application filed of even date herewith in the name of T. J. Judge, Ser. No. 517,339, dated January 7, 1944, and attention is directed to such application for a more complete understanding of this particular application of the signal.

30 The above rather specific description of one form of this invention is given solely by way of example, and is not intended, in any manner whatsoever, in a limiting sense. It is to be understood that various modifications, adaptations and alterations may be made from time to time, to meet all requirements of practice and expediency without, in any manner, departing from the spirit and scope of this invention, except insofar as it 40 may be limited by the appended claims.

45 Having described my invention, I now claim:

50 1. In a light signal of the search light type, a pivoted shaft, a member carried by the shaft, two spaced operating members each including an electro-magnet and an armature movable from a retracted to an attracted position, a rigid floating lever pivoted at each end, respectively to the armatures, a crank on the shaft, a stem connecting the crank to an intermediate point on the 55 lever, and a rigid loading arm fixed to one armature and extending across to bear against the lower face of the other armature when both armatures are in retracted positions.

60 2. In a light signal of the search light type, a pivoted shaft, a member carried by the shaft, two spaced operating members each including an electro-magnet and an armature movable from a retracted to an attracted position, a rigid floating lever pivoted at each end, respectively to the 65 armatures, a crank on the shaft, a stem connecting the crank to an intermediate point on the lever, a rigid loading arm fixed to one armature and extending across to bear against the lower face of the other armature when both armatures 70 are in retracted positions, and means associated

with the electro-magnet of said other armature for making its armature slower to act than said one armature and also slower to pick up than to release.

3. In a light signal of the search light type, a pivoted shaft, a member carried by the shaft, two spaced operating members each including an electro-magnet and an armature movable from a retracted to an attracted position, a rigid floating lever pivoted at each end, respectively, to the armatures, a crank on the shaft, a stem connecting the crank to an intermediate point on the lever, and a rigid loading arm fixed to the armature of one electro-magnet and extending across to bear against the lower face of the armature of the other electro-magnet when both armatures are in retracted positions, means associated with said one electro-magnet for making its armature slower to act than is the armature of said other electro-magnet and also slower to pick up than to release, and means associated with said other electro-magnet for polarizing it so that its armature responds only to current of a particular polarity.

4. In a light signal of the search light type, a shaft, a device on the shaft and biased to a first position and movable to second and third positions, two operating members for the device each including an electro-magnet and an armature, means operatively connecting each armature to the shaft so as to rock the shaft and move the device to its second position with a particular one of said armatures in attracted position and to its third position only when both said armatures are in attracted positions, and a rigid loading arm fixed to the other armature and bearing against the lower face of said particular armature when both of the armatures are in retracted positions.

5. In a light signal of the search light type, in combination, a shaft, a device on the shaft and biased to a first position and movable to second and third positions, two operating members for the device each including an electro-magnet and an armature one electro-magnet being polarized and the other non-polarized, means operatively connecting each armature to the shaft so as to rock the shaft and move the device to its second position with the armature of the non-polarized electro-magnet in an attracted position and to its third position only when both armatures are in attracted positions, circuit means for concurrently applying energy of either polarity to the two electro-magnets, means making the non-polarized magnet slower to act than the other magnet and also slower to pick up than to release its armature, and a rigid loading arm fixed to the armature of the polarized magnet and bearing against the lower face of the armature of the non-polarized electro-magnet when both armatures are in their retracted positions.

6. In a light signal of the search light type capable of displaying different indications in accordance with the position of a movable element, a polarized electro-magnet and a non-polarized electro-magnet each having an armature movable from a biased position to an attracted position upon the energization of that electro-magnet, said polarized electro-magnet requiring energization by a particular polarity in order to actuate 65 its armature to an attracted position, operating

means controlled by said armatures for causing said element to assume a first position when both said armatures are in their biased positions, for causing said element to assume a second position when the armature of said non-polarized electro-magnet is in an attracted position, and for causing said element to assume a third position when both of said armatures are in attracted positions, a mechanical means associated with the armature of said polarized electro-magnet and acting independently of said operating means for preventing the movement of that armature to an attracted position while the armature of said non-polarized electro-magnet is in its biased position, and means including a short circuited winding associated with said non-polarized electro-magnet for rendering its armature slow to respond to the energization and deenergization of that electro-magnet.

7. In a light signal of the search light type capable of displaying different indications in accordance with the position of a movable element, a polarized electro-magnet and a non-polarized electro-magnet each having an armature movable from a biased position to an attracted position upon the energization of that electro-magnet, said polarized electro-magnet requiring energization of a particular polarity in order to actuate its armature to an attracted position, operating means controlled by said armatures in their biased positions for causing said element to assume a first position, but causing said element to assume a second position when the armature of said non-polarized electro-magnet is in an attracted position and causing said element to assume a third position when both of said armatures are in attracted positions, a mechanical means separate from said operating means and associated with the armature of said polarized electro-magnet for preventing the movement of that armature to an attracted position while the armature of the non-polarized electro-magnet is in its biased position, a copper slug associated with said non-polarized electro-magnet for rendering its armature slow to respond to the energization and deenergization of that electro-magnet, and polarized circuit means for at times energizing said electro-magnets in series, said circuit means including a rectifier for always energizing said non-polarized electro-magnet in the same direction, whereby a quick reversal of polarity in said circuit does not result in the release of the armature of said non-polarized electro-magnet, and whereby said polarized electro-magnet can actuate its armature to an attracted position only when said circuit means is energized with a particular polarity and then only if the armature of said non-polarized electro-magnet has been actuated away from its biased position.
